OVERSHOE

Dolph G. Hoyt, Jr., Los Angeles, Calif.

Application July 3, 1952, Serial No. 20,455

Term of patent 14 years

(Cl. D7—4)

To all whom it may concern:

Be it known that I, Dolph G. Hoyt, Jr., a citizen of the United States, residing in Los Angeles, in the county of Los Angeles and State of California, have invented a new, original, and ornamental Design for an Overshoe, of which the following is a specification, reference being had to the accompanying drawing, forming a part thereof.

Figure 1 is a perspective view of my overshoe showing my new design.

Figure 2 is a perspective view showing the other side of the overshoe shown in Figure 1.

Figure 3 is a side elevational view showing the overshoe in an open position.

Figure 4 is a side elevational view of the overshoe in an open position as in Figure 3, but illustrating the opposite side of the overshoe.

Figure 5 is a top plan view of the overshoe.

I claim:

The ornamental design for an overshoe, substantially as shown.

DOLPH G. HOYT, JR.
